UNITED STATES PATENT OFFICE

CHARLES A. KITZMILLER, OF OAKLAND, CALIFORNIA

PORTABLE EQUIPMENT FOR COURSING PARKS

Application filed August 25, 1928. Serial No. 202,027.

This invention relates to equipment for coursing parks where a mechanical quarry as a lure is employed, and it consists in the novel construction, arrangement and combination of parts hereinafter described, and later claimed.

My object is to provide such equipment, removable, sectional, and portable in character, so that after once having been assembled and used in one locality, it may be quickly, easily, and economically dismantled and transported to another locality, and be reassembled for use again, regardless of the configuration or superficial area of the recreation site where used. By reason of its mobility, my equipment may be used in one locality after another, without the monetary losses which are incident to the heretofore permanent installments of such equipment; and with but one capital investment a large territory may be covered, and localities may be served which otherwise would not be reached.

In order that my invention may be readily understood and carried into effect, the same is hereinafter described with reference to the accompanying drawings, in which similar numerals indicate like parts. Of such drawings,

Fig. 1, is a perspective of my equipment installed;

Fig. 2, is a sectional elevation,—poles stripped of boundary fences;

Fig. 3, is an end elevation of one outer boundary post,—fence and protective panels in place;

Fig. 4, is an outside elevation of a portion of Fig. 3, showing fence hangers and method of joining fence panels;

Fig. 5, is an inside elevation of one section of protective panels;

Fig. 6, is an inner elevation of one of the inner boundary posts showing fence panels in place;

Fig. 7, is a cross section of Fig. 4, on the line A—A;

Fig. 8, is a plan of the yoke supporting protective panels;

Fig. 9, is a sectional elevation of Fig. 8.

In general, A represents an electrically

driven motor-car; B a central control station for the car; C a racing course for hounds between sectional boundary fences; D a starting-box for hounds; and E a judges' stand.

In detail, my construction is as follows: Integral with posts, 2, intended for use on the outer boundary of the coursing park, are annular plates, 3, to which are bolted channel-irons, 4, which serve as footings for said posts and ties for parallel rails, 5, upon which a motor-car, A, is adapted to travel. Extending outward from said car is an arm, 6, adapted to support at its tip, 7, an object (not shown) suitable for use as a quarry, or lure, for the hounds. The car is electrically driven by power supplied to it from a central control station, B, (Fig. 1), either through a conventional trolley-wire, 8, and trolley, 9, or third-rail, 10, and brush (not shown). The rails constituting the track for the car are further held in position by supplemental ties, 11, and are in jointed pairs. One end of each pair of rails is bolted to said channel-irons, as at 12, while the other end, 13, is free; the successive pairs of rails are joined together by means of fishplates, 14.

Intended for use on the inner boundary of the course are posts, 15, adapted to be imbedded in the ground, and provided with a removably secured stiff brace, 16, and an adjustable turn-buckle brace, 17. Both braces are provided with eyelets, 18, adapted to receive a pin, 19, which serves to anchor said posts in the ground. Interposed between said posts and removably attached thereto are panels comprised of rectangular frames, 20, covered with substantial wire screening, 21. These panels are placed vertically, and when assembled said posts and panels constitute a sectional fence which marks the inner boundary of the course.

Interposed between and supported by said posts, 2, are panels comprised of rectangular frames, 22, covered with heavy wire screening, 23. Said panels are removably supported on bifurcated hangers, 24, affixed to said posts by bolts, 25. As the upper portion of each side piece of said frames is bent slightly inward, as at 26, when the panels

are hung pressure is required to secure a perfect contact between the upper strips of the said frames and said hangers, the resultant effect being equivalent, in function, to that of a wedge. Said rectangular panels are placed in a vertical position on the outside of said posts, 2; and posts and panels, when assembled, constitute a sectional fence which marks the outer boundary of the course.

10 Removably hung on the inside of said posts, 2, by means of hooks, 27, adapted to hook into eyelets, 28, suitably affixed to said posts, are protective panels consisting of two portions, 29 and 30, hinged together, as at 31; each 15 portion being comprised of rectangular frames covered with heavy wire screening. Portions 29 of said protective panels are supported at the bottom by yokes, 32, threaded on the ends of pipes, 33, as at 34; the other 20 ends of said pipes fit freely over and are supported by stud bolts, 35, affixed to said posts. Said pipes also afford support for said trolley wire. Said yoke is sufficiently wide to receive the side pieces of two of said portions 29. When assembled, portions 29 are held by gravity in a fixed position inclining downward, and portions 30 hang free in a vertical position. The protective panels serve as a protective covering for the track 25 and car, and eliminate any possibility of contact between the hounds and the moving car when the race is in progress.

The lane between the boundary fences constitutes the racing course, C, coursed by the 30 hounds. The above-described posts terminate in standard supports, 36, for flood-lights, 37, serviceable for use when my equipment is used for night racing. All fencing is open 35 wire screening, thus affording visibility for spectators stationed at any point on the course.

40 As portions of my equipment, i. e., motor-car track, protective panels, outer and inner boundary fences, are sectional, the linear foot 45 dimensions of the course may either be increased or decreased by adding or removing sections as desired. For these reasons it may be readily adapted and used on recreation sites of varying configuration and superficial 50 area without further expense.

I would have it understood that the construction herein illustrated and particularly described is intended to exemplify what is at present regarded to be the preferred embodiment of my invention, and that the invention may be otherwise and variously embodied without departing from its spirit or the scope of the subjoined claims.

Having thus described my invention, what 60 I desire to claim and to secure by Letters Patent is:-

65 1. Portable equipment for coursing parks, comprised of sectional boundary fences for establishing the limits of a coursing track, the same consisting of poles and panels, said

70 panels consisting of rectangular frames supporting wire screening, bifurcated hangers affixed to said poles for removably supporting said panels, footings for said poles, a movable lure, mechanism for moving said lure around the course, the same consisting of a controllable movable car carrying a supporting arm for said lure, a series of sectional tracks for said car, and protective panels for said tracks.

75 2. In portable equipment for coursing parks, boundary fences comprised of poles and panels for establishing the limits of a coursing track, bifurcated hangers affixed to said poles for removably securing said panels, footings for said poles, a movable lure, mechanism for moving said lure around the course, the same consisting of a controllable movable car carrying a supporting arm for said lure, a track for said car, protective panels for said track, and means for increasing or decreasing the linear foot dimensions of the course in order to conform to varying conditions of configuration and superficial area of the site where said equipment is used.

80 3. In equipment for coursing parks, portable boundary fences comprised of poles and panels for establishing the limits of a coursing track, bifurcated hangers affixed to said poles, footings for said poles, a movable lure, mechanism for moving said lure around the course, the same consisting of a controllable movable car carrying a supporting arm for said lure, a portable track for said car, protective panels for said track, means for assembling and dismantling said equipment without destruction of parts, and means for increasing or decreasing the linear foot dimensions of the coursing track to meet varying configurations and areas of sites where used.

85 4. Portable equipment for coursing parks, comprised of parallel fences for establishing the limits of a coursing track and consisting of poles and sectional panels in series, said panels consisting of rectangular frames supporting wire screening, bifurcated hangers affixed to said poles for removably supporting said panels, footings for said poles, an artificial lure adapted to traverse said course, a movable car provided with an arm support for said lure, a series of sectional tracks for said car, a series of sectional protective panels for said car and tracks, said protective panels consisting of hinged rectangular frames covered with wire screening and removably attached to one series of poles, and a control for governing movement of the car.

90 In testimony whereof, I have hereunto set my signature.

CHARLES A. KITZMILLER.
